ABSTRACT

An equalizer for linearizing a non-linear phase-frequency characteristic and formed from successive all-pass filter stages in which at least first and second odd order filter stages align groups of frequencies along respective linear phase-frequency approximation through the introduction of appropriate symmetrical phase shifts. A third even order filter stage linearly superimposes the linear approximations by way of an antisymmetrical phase shift.

**EQUALIZER FOR LINEARIZING A
TRANSMISSION CHANNEL PHASE-FREQUENCY
RESPONSE UTILIZING ODD AND EVEN ORDER
ALL-PASS NETWORKS**

BACKGROUND OF THE INVENTION

This invention relates to an apparatus for linearizing the phase shift versus frequency response of a data or telephone transmission channel, said apparatus being formed from one or more filter stages having transfer functions of predetermined frequency polynomial degree or order.

In data or telephone transmission one of the channel characteristics that limits transmission rate is the phase - frequency distortion. By this, it is meant, the distortion due to the deviation from direct proportionality of phase shift versus frequency of the several frequency components of an applied electrical signal. Now consider the effect such a linear phase - frequency characteristic has upon the n harmonically related frequencies of any periodic waveform. The nth harmonic will suffer a phase shift n times that of the fundamental. Since the period of the nth harmonic is $1/n$ times that of the fundamental should be the same. Thus, generally speaking, the time delay of any transmission path varies as the slope of its phase - frequency characteristic. This assumes, of course, a channel, or for that matter a filter transfer function in which the relative amplitude does not vary with frequency. At this point, the term transfer function $H(s)$ of any circuit or system is defined as the ratio of output signal to input signal as a function of certain network parameters such as impedances, frequency, etc., were s is the generalized frequency.

One well known network which possesses the properties of relative amplitude invariance to frequency is called an "all pass" network.

To appreciate some of the properties of this network, a brief inquiry is made into a low order arrangement. This includes an excursus into phase and frequency.

The "all pass" transfer function has a magnitude K that is constant for all frequencies. The networks are denominated "even" or "odd" order according to the degree of the rational polynomial in the numerator or denominator of the transfer function. A typical "even order" function may be expressed as

$$H(s) = \frac{K \frac{s^2 - \alpha s + \omega_0^2}{s^2 + \alpha s + \omega_0^2}}{s^2 + \alpha s + \omega_0^2}$$

where $\alpha + \omega_0$ are positive constants.

This means that

$$\left| \frac{s^2 - \alpha s + \omega_0^2}{s^2 + \alpha s + \omega_0^2} \right| \approx 1$$

to satisfy the "all pass" requirement.

Now let $s = j\omega$
Then $H(j\omega) = K \frac{(\omega_0^2 - \omega^2) - j\alpha\omega}{(\omega_0^2 - \omega^2) + j\alpha\omega}$

Let θ represent the phase angle between the real component $(\omega_0^2 - \omega^2)$ and the corresponding imaginary component $(j\alpha\omega; - j\alpha\omega)$. This may be vectorally represented as

From this, it is apparent that

$$\theta = -\tan^{-1}(\alpha\omega)/(\omega_0^2 - \omega^2)$$

The total phase shift ϕ between output and input is equal to -2θ i.e.,

$$\phi = 2\theta = -2\tan^{-1}(\alpha\omega)/(\omega_0^2 - \omega^2)$$

From a design view point, it is recognized that the coefficients of the middle term of the transfer function i.e., α are not identical. Also the function $H(\omega)$ may be represented by

$$(s^2 - B\alpha S + \omega_0^2)/(S^2 + \alpha S + \omega_0^2)$$

In this form the numerator still approximates a second order damped resonant system and presents to the designer two design variables that of the damping factor B and natural frequency ω_0 .

While the properties have been known for some time, the lack of practical implementation of "all pass" networks has retarded their employment in the filter art. This may have been occasioned by the relative high cost of the precision passive components. This disadvantage has been remedied in part by the teachings in the copending application Ser. No. 050500, filed on June 29, 1970, entitled "Second Order R-C Equalizer Using One Operational Amplifier" in the name of W. G. Crouse and L. C. Haas. Further reference to "even" and "odd" order all-pass networks is briefly made in "Synthesis of Passive Networks" by Ernst A. Guillemin, John Wiley and Sons, New York, 1957 L.C. 57-8886 at pages 513 and 626 in a discussion of the physical realizability of transfer functions based upon the lattice. Also, "even" order functions are shown in the IBM Technical Disclosure Bulletin, Vol. 13, No. 11 at pages 3419-20, April, 1971. In this reference, successive "even" order filter stages form a delay equalizer in which individual stages may be electronically removed from the equalizer for testing purposes. In subsequent discussion, attention is primarily related to the phase ϕ versus frequency (ω, F) characteristic. Consequently, the transfer function $H(\omega)$ will be referenced generally and not specially.

SUMMARY OF THE INVENTION

It is an object of this invention to devise an equalizer for linearizing the phase versus frequency response characteristics of a transmission channel, the apparatus being formed from one or more "all pass" filter stages having transfer functions of predetermined frequency polynomial degree or order. More particularly, it is the object to secure the phase alignment of several predetermined frequencies as an index of the phase - frequency linearity.

The foregoing objects of this invention are satisfied by an equalizer embodiment formed from successive all pass filter stages in which at least a first and second fil-

ter stage are of odd order for aligning groups of frequencies along respective linear phase - frequency approximations. A third filter stage of even order linearly aligns by way of superposition the first and second approximations.

Each all pass filter stage can have its output to input signal ratio termed a transfer function $H(\omega)$ represented by rational polynomials of frequency with constant coefficients. Such polynomials can be factored into products of complex frequency terms $\omega^2 - \omega_i^2$. As previously mentioned when discussing the polynomial of the second degree even order, the frequency terms in turn can be partitioned into so called real (resistive) R and imaginary (reactive) X parts. The imaginary or reactive component can be related to $H(\omega)$ as

$$X = H(\omega) \left[\frac{\pi(\omega^2 - \omega_i^2)}{\pi(\omega^2 - \omega_j^2)} \right]$$

Those values of angular frequency $\omega = \omega_i$ or $\omega = \omega_j$ which reduce the function to singularities are termed "pivots". One of the properties of each filter stage is that at the "pivot points" the phase angle is always a multiple of π radians. Now the phase shift $\Delta\phi$ introduced by the stage varies as the arctan

$$\left[\frac{H(\omega)}{R} \frac{\pi_1^n(\omega^2 - \omega_i^2)}{\pi_1^m(\omega^2 - \omega_j^2)} \right]$$

Referring to the arctan function, an odd order filter stage arises when $n-m$ is one. Likewise an even order stage occurs when $n-m$ is zero. Now the angular frequencies ω are related to frequency F by $\omega = 2\pi F$, $\omega_i = 2\pi F_i$, $\omega_j = 2\pi F_j$, where for the pivot points ($\Delta\phi$) $i = 2i\pi$ and $(\Delta\phi)_j = (2j-l)\pi$ for $i, j = 1, 2, \dots$

The invention contemplates linearizing a phase - frequency characteristic by aligning a group of frequencies along a linear approximation to the original characteristic. The alignment consists of introducing sufficient delay to alter the characteristic so that the frequencies of the characteristic represented by the pivot points in the all pass filter arctan function can be connected by a line of constant slope. For a highly nonlinear characteristic, it has been found expedient to use successive odd order all pass filter stages to separately align different groups of frequencies. To assist in the final alignment, it is further expedient if successive stages have some common or overlapping pivot points. The piecewise linearization by odd order stages results in a substantially straightened characteristic approximated by lines of different slopes. Lastly, an even order all pass stage is used to align the separate linear approximations.

The odd order all pass networks introduce a "symmetrical" phase shift.

This phase shift is measured along the phase ordinate between the linear approximation and the phase characteristic. The linear approximation is obtained by connecting two extreme frequencies (pivot points) of the characteristic and an intermediate frequency (i.e., arithmetic means). The term "symmetrical" means that the phase shift introduced will be nearly the same in magnitude and direction along the frequency range of interest. Similarly, the even order networks introduce an antisymmetrical phase shift. In this regard, the phase shift will be the same in absolute magnitude but of opposite direction as measured from the intermediate frequency.

BRIEF DESCRIPTION OF THE DRAWING

FIG. 1 is a schematic diagram of a simple all-pass filter stage using an operational amplifier.

FIG. 2 shows one embodiment of the invention utilizing successive odd order and even order filter stages.

FIG. 2a features an all-pass filter stage having a positive resistive portion compensated by negative resistance circuits.

FIG. 3 exhibits the symmetrical phase shift of an order 3 filter stage.

FIG. 4a exhibits the symmetrical phase shift of an order 5 filter stage.

FIG. 4b shows the corresponding positional relationship of the phase characteristic of the order 3 filter stage with that of the order 5 stage of FIG. 4a.

FIG. 4c represents the combined order 3 and order 5 phase characteristics. FIG. 5 is the antisymmetrical phase shift of an order 4 filter stage.

FIGS. 6 - 9 show the successive steps in phase alignment of the embodiment of FIG. 2.

FIGS. 10 - 12 relate to the phase alignment of the embodiment found in FIG. 13.

FIG. 13 shows a second embodiment of the invention utilizing odd and even order filter stages.

DESCRIPTION OF THE PREFERRED EMBODIMENT

Referring now to FIG. 1, there is shown a schematic diagram of an all-pass filter stage. This stage comprises an operational amplifier OPAM, resistive elements R_0 and R, and a reactive impedance network X. The reactive impedance X is of the dipole form. That is, its impedance function can be factored as complex conjugate impedance $(\omega^2 - \omega_1^2)(\omega^2 - \omega_2^2)$.

The nature of dipole X determines the number of pivot points, and the variation of $\Delta\phi$ versus the frequency for a given R. Thus, various types of filter stages are obtained. Such stages are called stages of the third order, fourth order, fifth order, etc. This order notion results from definitions in the study of basic all pass networks differing from one another in dipole X. The differences were particularly in the impedance mathematical poles of this dipole. In a more simple way, it should be noted that for an all pass filter stage, the number of pivot points is one unit below the order number. Relatedly, FIG. 2 shows a series of third, fourth, and fifth order stages embodying the invention.

For multiple reactances the constitution of dipole X becomes complicated. It is not purely reactive. That is, a positive real (resistive) component is exhibited. One can consider the possibility to compensate its ohmic section by negative resistance circuits now produced more easily by using new techniques. Such a compensation is shown in FIG. 2a. This is a schematic diagram of an order 5 stage with correction by means of negative resistance elements.

It should be noted that, nevertheless, the whole stage remains sufficiently and uniformly damped so that parasitic oscillations are avoided. Such compensation can be applied to a stage of any order. The necessity for this increases with the order of the filter stage.

An order 3 filter stage (one example of which is given in FIG. 2) has a phase curve showing two pivot points at frequencies F_1 and F_2 and introduces a phase shift given by formula 1 indicated in FIG. 3, where m is a variable coefficient proportional to $1/R$. Such a filter

65 in FIG. 2) has a phase curve showing two pivot points at frequencies F_1 and F_2 and introduces a phase shift given by formula 1 indicated in FIG. 3, where m is a variable coefficient proportional to $1/R$. Such a filter

stage may be used to adjust phase in a frequency range by ensuring the correspondence of the extreme frequencies of this band with $F1$ and $F2$. Curve $Cr\ \delta 1$ gives the shape of the phase - frequency characteristic curve and corresponds to a particular use in the scope of the device of FIG. 2. In the same way, FIG. 4a relates to an order 5 filter stage. This type of stage encompasses four pivot frequencies $F'1, F'2, F'3, F'4$. The phase shift introduced thereby is given by formula 2 (FIG. 4a) where n is a coefficient which can be compared to coefficient m of formula 1 (FIG. 3).

FIG. 5 relates to a fourth order all pass filter stage. This type of stage comprises three pivot frequencies $F''1, F''2, F''3$. It introduces a phase shift given by formula 4 (FIG. 5), where q is a coefficient which can be compared to coefficients m and n of the previous formula. Curve $Cr\ \delta 3$ gives the shape of the phase - frequency characteristic.

Before proceeding further, it is necessary to define two notions: the notion of "symmetrical phase shift" or "phase shift symmetry". If one considers FIG. 3, frequencies F_m and F_M are symmetrical with respect to central frequency F_c for a determined function $\Delta\phi(F)$. For example, for the curve $Cr\ \delta 1$, it appears that the shift between the phase shift given by the circuit and the linear shift is almost the same in absolute value and in the same direction for the points corresponding to F_m and F_M . Such a phase shift is called "symmetrical phase shift". It is possible to make the same observation with the phase shift given by an order 5 stage in FIG. 4a.

Now, one has to consider the phase shift given by an order 4 stage shown in FIG. 5. Frequencies F_m and F_M are symmetrical with respect to central frequency $F''2$. The change between the phase shift given by the circuit and the linear shift is almost the same in absolute value but it is of opposite direction. Such phase shift is called "antisymmetrical phase shift". Stages or groups of filter stages giving a "symmetrical phase shift" are called "symmetrical type stages"; in the same way, filter stages or groups of stages giving "antisymmetrical phase shifts" are called "antisymmetrical stages".

It is possible to associate several of these stages by selecting their pivot points judiciously while keeping their variable parameters independent one from the others. If on the contrary, y stages are of same type or of various types, by applying $(y-1)$ additional conditions, $(y-1)$ relations will finally be obtained between y coefficients. Consequently, an all pass type circuit with new properties will be obtained both with respect to the pivots as well as to the "symmetry" or "antisymmetry" of the phase shift given by said circuit. This new circuit will still have one degree of freedom as does a single stage. When considering, for example, an order 3 stage and an order 5 stage, if one designates by $\Delta\phi_3x$ and $\Delta\phi_5x$ the phase shift given by them respectively at a given frequency F_x , it is possible to have the total phase shift $\Delta\phi_x$ constant as R varies. Illustratively, $\Delta\phi_x = \Delta\phi_3x + \Delta\phi_5x = 2K$, which gives from formula 1 and 2, $2 \arctan mAx + 2 \arctan nBx = 2K$. Let $Ax = A(F_x)$ and $Bx = B(F_x)$ from which formula 5 is obtained

$$(mAx + nBx)/(1 + mn AxBx) = \tan K$$

(5)

This is a relation between m and n .

In the case when the extreme pivots are the same, $F1 = F'1$ and $F2 = F'4$, when

$$Fx = (F'1 + F'4)/2 = F_c$$

and if a permanent compensation is wanted for shift δ' and δ'' as they appear on associated FIGS. 4a and 4b (corresponding respectively to the combined order 5 and order 3 stages), is obtained a circuit the pivot points of which are those given on FIG. 4c, the phase shift of which, in $(F'1 + F'4)/2$ is 2π . The equation (5) above becomes $m\ Ac + nBc = 0$

$$m/n = -Bc/Ac = \gamma = \text{constant}$$

In this case, the relationship between m and n is very simple. This allows an easy coupling between the physical elements, the variations of which involve the variations of m and n . These elements correspond to the variable resistances R of each stage. In FIG. 2, these variable elements have been schematically shown in 15 potentiometric form; any equivalent form such as, for example, the switching of resistances in or out, may be adopted. The circuits for carrying out said connection or variation may be of any type and their control may be analog or digital. This remark is not restrictive and 20 applies to all possible uses of the invention.

To come back to the combination stage formed from an order 3 stage and of an order 5 stage, it is difficult to define the order of such a circuit. Nevertheless, as it is composed of odd order stages we say that this circuit is of "odd order". Similarly, circuits composed of even order stages will be found and they will be defined as being of "even order".

Concerning the combined order 3 and order 5 stage, it appears that the phase shift is a "symmetrical" phase 25 shift as shown by the curves of FIG. 4c. It is given by formula 3 of the same figure.

Filter stages of either the simple or complex type enable phase correction. In order to obtain a linear phase shift between several consecutive frequencies; the phase values for these frequencies are said to be "linear" because they lie upon the same straight line.

Referring now to FIGS. 6, 7, and 8, there are shown dynamic illustrations of the invention. Suppose the frequencies $f1, f2, f3, f4, f5$ and original phase curve Co define a transmission channel. One will align the value for $f3$ with the ones for $f1$ and $f5$ by using an order 3 stage. This will compensate shift $\delta 1$ and will have $f1$ and $f5$ as pivot points. Curve $Cr\ \delta 1$ of FIG. 3 corresponds to the filter stage where $F1=1$ and $F2=f5$. At the output of this stage, curve Co becomes curve $C1$ where points $f1, f3, f5$ are aligned.

The following operation consists in the alignment of points $f2, f3, f4$ independently of the alignment of points $f1, f3, f5$ which will be maintained in this operation. To align $f2, f3, f4$, it is enough to correct shift $\delta 2$, as shown on FIG. 7 on which we have plotted curve $C1$. This correction will be carried out by using a circuit having points $f1, f3, f5$ as pivots and showing a "symmetrical" phase shift. To perfect this alignment a compound odd order stage of order 3 and order 5 stages is used. Curve $Cr\ \delta 2$ of FIG. 4c is the curve which corresponds. At the output of this circuit, phase curve $C1$ becomes curve $C2$ (FIG. 7); the points corresponding to $f1, f3, f5$ are aligned, the points corresponding to $f2, f3, f4$ are also aligned with respect to line d . The points corresponding to $f2$ and $f4$ show, with respect to alignment $f1, f3, f5$, two respective shifts $\delta 3$ and $-\delta 3$, as

shown in FIG. 8 where we have plotted curve C2. Thus, all the points will be aligned by correcting this shift with a filter stage having points f_1, f_3, f_5 as pivots and giving an "antisymmetrical" type phase shift. It is exactly the case of the order 4 stage previously studied. Curve Cr 83 in FIG. 5, gives the type of phase shift and the values of which, taken as an example, are the values corresponding to shift δ_3 . At the output of this stage, phase curve C2 becomes curve C3 (FIG. 8) where the points corresponding to f_1, f_2, f_3, f_4, f_5 are aligned. The curve C3 has been substituted to curve C0 by using an assembly composed of an order 3 stage, a group of order 3 and order 5 coupled stages and an order 4 stage. This is exactly the one shown in FIG. 2.

The evolution from C0 to C3 was studied with the cells geographically placed in the same order as the operations carried out. In fact, one acts on the cells by testing the result at output S and the final result consists to obtain, at output S, curve C3 of FIG. 8, the typical points of which are plotted in FIG. 9. If this final result depends on the following of the operations, it does not depend on the geographical position of the circuits performing these operations. Suppose, for example, circuits I, II, and III following order II, III, I indicated in FIG. 9 which also gives various positions of the typical points of the phase curve at outputs S in accordance with the successive operations. Independently of any adjustment value, from the original phases at points E (points marked with a cross), the three circuits give, at the output for f_1 and f_5 which are the common extreme pivot points, the phase values at 10 and 11. On starting, taking into account the arbitrary original adjustments, the phase value for f_3 is itself arbitrary. The first operation carried out is the action on circuit I which aligns at 12 this phase value with values 10 and 11. The following operation consists to act on circuit II and this operation should maintain alignment f_1, f_3, f_5 which has been just obtained (we say that it transfers it) and is also going to align, on another line, points f_2, f_3, f_4 . Circuit II having points f_1, f_3, f_5 as pivots, its action on the phases of these frequencies is independent of its adjustment. Thus the phases in E' of frequencies f_1, f_2, f_5 would not change; circuit III having also points f_1, f_3, f_5 as pivots, the phases of these frequencies at E'' will not change. Thus, it appears that the action on II and the following action on III do not modify the adjustment just carried out at I, the phase of f_3 remains aligned at 12. By acting on II, symmetrical modifications are applied to the phase of f_2 , and f_4 in E'; III being unchanged. These modifications involve equivalent symmetrical modifications at E'', which in turn, involve symmetrical modifications at output S since I which has been adjusted remains unvariable. Then, one will act on II until obtainment at S of an alignment of the phases of f_2, f_3 , and f_4 , the alignment of f_1, f_3, f_5 being maintained as previously seen. At this time, it exists at S, the distribution 10, 12, 11 previously obtained and the distribution 14, 12, 15 which has just been obtained by acting on II. The, input E' of circuit III receives f_1, f_3, f_5, f_2, f_4 with well determined phases by acting on III. The phases of f_2 and f_4 at E'' are submitted to two antisymmetrical variations which will involve equivalent antisymmetrical variations at S, which cause the rotation of straight line 14, 12, 15 around 12. The positions of points 14, 15 being always the intersection of said straight line with vertical f_2 and f_4 ; one acts on III until points 14, 15 come to 16 and 17. At this

time, the wanted alignment 10, 16, 12, 17, 11 is obtained which corresponds to curve C3 of FIG. 8.

This description of the present invention has been given as an example and it will be understood that various changes in form and details may be made therein without departing from the spirit and scope of the invention.

What is claimed is:

1. An equalizer for linearizing the phase-frequency response (FIG. 6 - C_0) of a transmission channel to an applied signal, the channel having a bandwidth containing preselected frequencies ($f_1 < f_2 < f_3 < f_4 < f_5$), the equalizer being characterized by successive all pass filter stages comprising at least:

first (FIG. 2 - ckt. I) and second (FIG. 2 - ckt. II) odd order filter stages for symmetrically phase shift aligning different respective groups of preselected frequencies (FIG. 6 - Δ_1, f_1, f_3, f_5 ; FIG. 7 - Δ_2, f_2, f_3, f_4),

at least one frequency of each group being in common (f_3), to conform to predetermined linear phase - frequency approximations (C1, C2); the first odd order filter including means for aligning an odd number of alternate ones of the preselected frequencies (f_1, f_3, f_5) as arranged in order of increasing magnitude, the second odd order filter including means for aligning an odd number of consecutive preselected frequencies (f_2, f_3, f_4) also arranged in order of increasing magnitude; and an even order filter stage (FIG. 2 - ckt. III) for antisymmetrically phase shift aligning the previously phase aligned frequency groups about their common frequency.

2. An equalizer for linearizing the phase - frequency response (FIG. 6 - C_0) of a transmission channel to an applied signal, the channel having a predetermined bandwidth ($f_1 < f_2 < f_3 < f_4 < f_5$), said equalizer being characterized by successive all-pass filter stages, each filter stage having its phase shift $\Delta\phi$ varying as

$$\arctan \left[\frac{H(\omega)}{R} \frac{\pi_1^n (\omega^2 - \omega_i^2)}{\pi_1^m (\omega^2 - \omega_j^2)} \right]$$

where $n-m = 0$ for an even order phase shift, $n-m = 1$ for an odd order phase shift; and

where $\omega = 2\pi F$, $\omega_i = 2\pi F_i$, and $\omega_j = 2\pi F_j$ being the angular frequencies denominated pivot points, subject to the condition that $(\Delta\phi)_i = 2i\pi$ and $(\Delta\phi)_j = (2j-1)$ and $(i, j = 1, 2, 3, \dots)$, and R being the real part of the filter stage transfer function $H(\omega)$; the equalizer being further characterized by at least:

a first filter stage (FIG. 2 - ckt. I) for introducing an odd order phase shift (FIG. 6 - Δ_1) to align a first group of frequencies (f_1, f_3, f_5) along a first linear phase - frequency approximation to yield a first intermediate response characteristic (c1); a second filter stage (FIG. 2 ckt. II) for introducing an odd order phase shift (FIG. 7 - Δ_2) to align a second group of frequencies (f_2, f_3, f_4) along a second linear phase - frequency approximation (d) to yield a second intermediate response characteristic (c2); and

a third filter stage (FIG. 2 - ckt. III) for introducing an even order phase shift (FIG. 8 - Δ_3) to linearly align the first and second linear approximations to yield a final response characteristic (c3).

3. An equalizer according to claim 2, wherein the phase shift $\Delta\phi$ of the first filter stage (FIG. 3) varies as

$$\left[\arctan m \frac{F^2 - F_1'^2}{F(F^2 - F_2'^2)} \right]$$

the pivot points F_1 and F_2 coinciding with the respective extremes of the first group of frequencies (f_1 and f_3).

4. An equalizer according to claim 3, wherein the phase shift $\Delta\phi$ of the second filter stage (FIG. 4c) varies as

$$\begin{aligned} \arctan n \left[\frac{F^2 - F_1'^2}{F(F^2 - F_4'^2)} \right] \\ + \arctan n \left[\frac{(F^2 - F_1'^2)(F^2 - F_3'^2)}{F(F^2 - F_2'^2)(F^2 - F_4'^2)} \right] \end{aligned}$$

wherein the pivot points F_1' and F_3' coincide with the

lower extreme (f_1) and an intermediate (f_3) frequency of the first group, F_2' and F_4' coincide with frequencies of the second group, and $m = kn$.

5. An equalizer according to claim 2, wherein each odd and even order filter stage respectively produces a symmetrical and antisymmetrical phase shift as measured from a corresponding linear phase - frequency approximation connecting at least extreme and intermediate frequencies of the respective group.

6. An equalizer according to claim 1, wherein the first and second odd order stages and the even order stage are permutatively arrangeable.

7. An equalizer according to claim 2, wherein the first and second odd order stages and the even order stage are permutatively arrangeable.
